SAMPLING CAN

Stephen H. Brooks, New York, N. Y.

Application March 24, 1939, Serial No. 264,025

3 Claims. (Cl. 137—18)

My invention relates to improvements in sampling cans and it more especially comprises the features referred to in the accompanying claims.

5 An object of the invention is to provide an all-around-purpose sampling can that will enable a sampler to secure samples of the contents of a tank at the top level, at the bottom level and at any desired point between the extremes; and that also, in addition to securing the desired sample, the temperature of the sample is determinable at the same time.

With these and related objects in view I illustrate in the accompanying drawings such an instance of adaptation as will disclose the broad features of the invention without limiting myself to the specific details shown thereon and described herein.

Fig. 1 is a side elevation partly in section of the can unsuspended, and closed at top and bottom.

Fig. 2 is a side elevation partly in section of Fig. 1 showing the can suspended, closed at the top and open at the bottom.

25 Fig. 3 is a front elevation, partly in section showing the can open at the top.

Fig. 4 is a bottom plan of the lower end.

Fig. 5 is an enlarged elevation partly in section showing the opening of the valve in the bottom 30 of the can throughout the presence of the sampling bottle.

Fig. 6 is an enlarged elevation in section of the cap shown in Fig. 5.

Fig. 7 is a bottom plan view of Fig. 6.

35 Fig. 8 is a top plan view of the valve releasing means positioned in the cap.

In the actual production and use of my sampling can I may employ whatever alternatives or equivalents that the exigencies of varying 40 conditions may demand without departing from the broad spirit of the invention.

The sampling can may be made of a brass or other non-corroding metal tube 1. It has a removable top 2 and a bottom 3. The bottom includes a valve 4 that has a stem 5 which is held normally closed by reason of a spring 6 on the stem 5. The spring abuts the valve casing cross member 7 and a collar 8 on the stem. The stem 5 has movement in the cross member bearing 9. On each side of the cross member openings 10 are formed. These openings serve as ports for the entrance of liquid when the valve 4 is open. The portion 3 has depending protective fingers 11. A safety cap 12 encloses the bottom 3 when

it is not to be used to secure a sample of liquid from the tank at the lowest point of the tank.

The top 2 is attached to the tube by means of internal radial pins 13 which enter inclined grooves 14 formed on the outer face of the base 10 of this upper or top member. An opening 15 is formed to admit liquid at the top of the sampling well when the opening is unobstructed.

This top member 2 has two upstanding projections 16 which are each provided with two curved slots. The short slot 17 limits the position of the closure 18 in relation to the opening 15, maintaining the opening closed. The long curved slot 19 limits the extreme upward movement of the closure stem 18 when it is raised to 15 free the opening 15 to admit liquid to the can 1.

The closure stem 18 is slightly tapered at its lower end to lead it into the opening 15. At its upper end an hemispherical enlargement 20 is formed. This has two side bosses 21 into which the threaded end of the shoulder screws enter. The enlarged portions 22 are positioned in slots 17 or 19. These screws have heads 23 which prevent the enlargement 20 becoming disconnected from the slots 17 and 19. The enlargement 20 at its topmost surface has an eye 24 formed for the attachment of a snap 25 swiveled to the end of a strong flat tape line 26 which is attached to any desired form of winding device secured to the tank top (not shown). 30

After the can has been lowered into the liquid to any desired depth, noted from the indications on the tape line, at which a sample is to be taken a sudden slackening and a quick jerk of the tape line will bring the screws 22 into the long slot 19 35 thus uncovering the opening 15 and admitting liquid from the desired level. When sufficient time has elapsed to fill the can there is no need for specially closing it.

A thermometer 27 is secured on the inside of 40 the tube 1 by spring clips 28 in any desired manner. It supplies definite temperature data from any level of the tank contents.

The operation of my sampling can is very simple through the cooperation of a rapid closing gate valve in a pipe extension on the top of a tank. This has side openings above the valve through which the can is passed and secured to the free end of the tape line. The tape line is wound on the axle of a winch which is controlled 45 by an outside crank. These features relating especially to gas tight tanks are not shown herein as they constitute a separate invention. They are however described in an application, Serial No. 245,124, filed on December 12, 1938. Suffice 50 55

it to say the inherent mechanism of the sampling can and its operation is not limited to the exclusive use in gas tight tanks.

Sampling cans have been used in the oil industry for taking samples of tank contents in various ways by inefficient means of one primitive type or another. It is most important to obtain a sample of oil at any exact given depth of the tank because a tank having a given depth of 5 oil in it which has remained at this level without any movement for a period of six months will probably have become stratified to such an extent that differences of specific gravity will be found at the five, ten, fifteen, twenty, twenty-five foot 10 and other levels. In the oncoming use of pressure tanks this matter of stratification is very important. It is so important that samplers operated by means of two strings, as has been in 15 vogue, is entirely inadequate and impractical.

20 The cooperative use of a thermometer with my sampling can is a great advantage over prior existing temperature reading devices. In ordinarily taking the temperature of the contents of a tank the thermometer is lowered into the 25 tank and submerged in the oil. Should a forty-foot tank have only fifteen feet of oil in it by the time an unprotected thermometer is raised through the twenty-five feet of gas vapor space, which, under summer conditions may have a 30 temperature as high as 200 degrees Fahrenheit will show a resulting temperature that is many degrees higher than the temperature of the oil in the bottom portion of the tank. With my 35 combined sampling can such discrepancies cannot arise because the thermometer used is inside of the can in direct contact with the actual sample of oil brought to the top of the tank.

Should a graduated sample be desired the top 2 is swung into a tight fit on the tube 4, the tape line snap 25 is attached to the eye 24 of the enlargement 20 of the closure stem 18 and the can, in this position, is lowered into the tank and the oil regardless of its gravity permits the slow filling of the can in its downward progress, thus 45 securing an average sample of the tank's contents.

In case a sample is desired at any given level the closure stem 18 may be manually operated to change the position of screws 22 from slot 19 50 to the slot 17 so as to thus close the opening 15. The sampler finding the can at the desired point slacks the tape quickly for two or three inches, and immediately recatches it. In this condition, the can, being empty, it has considerable buoyancy and practically no weight, the effect of the sudden slack of the tape allows the ball 20 and its stem 18 to drop to its lowest position, when a sudden pull on the tape will raise it to its highest position so as to let oil flow 60 through the opening 15 to fill the can. A continued upward pull of the tape will bring the can to the top of the tank for observation.

The cooperative action of the curved interconnecting slots 17 and 19 is such that a movement 65 of the pivot screws 22 up and down in such slots will automatically reverse the position of the screws, that is, when the screws 22 drop in slot 17 to the lowest point the next pull upward on 20 will bring the screws to the top of the slot 19 leaving the opening 15 open to receive the desired sample.

When samples of the contents of tanks which 75 are of high gravity gasoline under high vapor pressure of ten to twenty pounds, are to be taken from the tank to be of service they must be

transferred from the sampling can to sampling bottles.

In ordinary practice the contents of large sampling cans are usually poured into sampling bottles by removal of the top of the can. This procedure causes the loss of a considerable part of the very light portions of the high gravity gasoline to evaporate into the air.

To avoid this loss the expedient shown in Figs. 5 to 8, is used. By means of this attachment to 10 the bottom of the can, instead of the cap 12 shown in Fig. 1, the highly volatile gasoline may be removed from the tank 1 directly into a sampling bottle from the bottom of the can instead of pouring it out from the open top of the can. 15

A supplemental cap 29 is screwed on the bottom of the can instead of the cap 12. This cap has a partition 30, a bottom recess 31, and a knurled rim 32. A central hole is formed in the partition 30 in which a stem 33 is free to move 20 by gravity. This stem at its upper end is slotted at 34 and an annular groove is formed on its outer surface to receive a split ring 35. At the lower end of the stem 33, it is threaded internally at 36 to receive a plug 37.

About midway of the length of the stem 33 a thin enlargement 38 is formed. It has openings 39 which are the same in number as the radial grooves 42 formed on the under face of the partition 30. The split ring 35 on the stem 33 30 rests against the upper face of the partition 30, which prevents the accidental removal or loss of the stem.

The highly volatile contents of the can are removed as follows. The cap 29 is screwed onto 35 the bottom of a full can and the plug 37 is removed from the bottom end of the stem 33, the stem resting in its lowest position. The projection 44 is placed into the open neck of the sampling bottle 40, and the bottle is then moved 40 upward against the enlargement 38. This causes the upper end of the stem 33 to engage the enlargement 8 of the valve stem 5. A further upward movement of the bottle until the enlargement 38 engages the underside of the partition 45 30, will open the valve 4 so that the contents of the can will flow through the opening 41 of the stem 33 into the sampling bottle, thus insuring that the highly volatile gasoline is removed from the sampling can without any evaporation losses. 50 The radial grooves 42 and the concentric groove 43, associated with the openings 39 of the disk 38 permit air to escape from the bottle.

Gasoline will flow freely from the can 1 into the bottle 40 by reason of the slot 34 of the stem 55 33 forming a free passage into the opening 41 of the stem. If the slot 34 were not formed then the upper end of the stem 33 engaging the underside of the enlargement 8 of the valve stem 5 would prevent the passage of gasoline.

What I claim is:

1. A sampling can containing highly volatile liquid having a spring-pressed valve at the lower end of the can, a removable cap to be attached and detached from the bottom end of the can 65 below the spring-pressed valve, a partition in the cap, a hollow stem subject to gravity having movement in an opening in the partition adapted to engage the spring pressed valve in the bottom end of the can, a stem for such valve, 70 and means for raising the valve when a sample bottle is pressed against the gravity stem.

2. A sampling can comprising a gravity inlet valve at the top of the can, a spring pressed closure valve at the bottom end, a cap having 75

5 a partition therein, a gravity tube movable in the partition, a notched upper end of the tube, an annular flange around the tube having air vent holes therein, said tube serving to move the spring-pressed closure valve upward into an open position through the tube being raised when a sampling bottle is pressed against it whereby any highly volatile liquid in the can is transferred to the bottle without the loss of 10 vapor while the sampling bottle is being filled and on the withdrawal of the bottle the parts are restored to their former position.

3. A sampling can comprising a tube, a gravity inlet valve at the top, a spring pressed closure valve at the bottom, a screw cap for the top of the can in which the gravity inlet valve is operative, a pair of upstanding projections having reversed curved slots therein, a pin extending from each side of the gravity valve entering into the slots of the projections and an eye on the gravity valve for suspending the entire tube from a measuring tape. 10
